ERNEST A. CRAIG, OF AUCKLAND, NEW ZEALAND.

STEAM GENERATOR.

Application filed August 13, 1919. Serial No. 317,135.

This invention relates to steam generators of the class described in my co-pending application, No. 284,657, filed March 24, 1919, in which the water is forced by a pump to advance in a single direction through a course of piping which is subjected to the heat of a furnace; the water reaching a very high degree of temperature and pressure being finally converted into steam and retained in the steam drum ready for use. The piping is jacketed with a heat-conducting refractory material, which may reach a high degree of heat, and may become incandescent, thus prolonging the life of the flames, which, in ordinary boilers, is found to become prematurely cooled and shortened by the relatively cool metal pipes. In said application the incandescent jackets impart heat to the pipes and the fluid therein, while said jackets remain highly heated at the portions thereof that are lapped by the flames, and hence the flames persist much longer, and combustion is made more complete, thus reducing or eliminating combustible carbon monoxide from the waste gases escaping from the furnace.

One of the objects of the present invention is to construct a simple and compact apparatus of the class described; to provide an improved flame chamber and flame passage, to extract a maximum of heating power from the fuel. Another object is to improve the construction of the flame chamber, which may be a chamber of the single combustion type, to secure increased efficiency; and the device may, if desired, operate as a gas producer, with provision being made for supplying air to mix with the carbon monoxide, to carry on secondary combustion, for heating certain of the water pipes in the system.

Another object is to construct and dispose the pipe coils in a manner to conduce to simplicity and economy of manufacture and accessibility of the piping, for inspection and cleaning.

In carrying out the present improvements, the fire chamber is placed at the center of the generator, and comprises a front wall, a rear wall and side walls. In each side wall is a coil of piping, forming part of the course through which the water is forced by the pump. The flames divide and pass over the tops of these side walls, and down through passages alongside of said walls; the latter

being thus heated on both sides, and the piping therein being hence subjected to extreme heat. The coils in these walls preferably constitute the final portion of the fluid course, and lead directly to the steam-drum at the end of the system.

The flames flow down said passages into flame chambers near the bottom of the apparatus, and thence rise between partitions which consist of heat-conducting refractory material, in each of which is imbedded a grid or coil of relatively fine piping. These grids form part of said water course or system. Waste gases escape from the tops of said passages between the partitions, passing up flues to the stack.

The steam-drum referred to may be placed at the central portion of the generator, above the fire chamber, where it will be superheated. Said steam-drum may be flanked by water drums in which is contained a reserve of water at the intake end of the generator; the pump forcing the water first into said water drums and thence through distributing headers into said grid sections, from which the fluid is collected by headers leading to the described coils in the side walls of the fire chamber, where the fluid receives its final access of heat before being delivered to the steam-drum.

Each coil is made up of lengths of piping, which are connected at their ends in a manner to give a zigzag course to the coil; screw plugs being provided in the front wall of the furnace for all of the coils in the generator.

Included in the apparatus set forth in said application is a reserve water drum, used for heating or maintaining the heat of the water as it advances through the system (in which said reserve water drum is included); the water in this drum being also available to enable the generator to keep on developing steam when the pump is temporarily shut down, or when for any other reason, there is an obstacle to the regular flow of water through the system.

In said application, the water reserve drum and steam-drum are connected by means of a tube or by-pass, in which is fitted a valve which is normally closed during the regular operation of the steam-generator, but which may be opened by the attendant whenever the pump is stopped, or whenever

any other occasion demands. This valve is also intended to be closed by the attendant when the pump is started again.

One of the objects of the present improvements is to avoid the necessity of having this by-pass-valve opened and closed by the attendant, who might forget or neglect to attend to the opening of the valve in emergency, thereby rendering the generator liable to collapse for lack of circulation of water therein.

According to the present improvements, the by-pass-valve is automatically controlled, being arranged to stand open when the pump is not working, as for example, when the generator is being warmed up. Upon starting the pump, the valve in the by-pass is automatically closed. Upon cessation of the operation of the pump, said valve automatically opens, so that safety of the generator is assured.

The two drums aforesaid are connected by a cross main, which is normally closed; but provision is made whereby at the closing down of the pump, said cross main or by-pass is automatically opened, thus connecting the water drums to each other and to the steam drum, thus permitting circulation to be set up by reason of the action of heat upon the water contained in the system.

Other features and advantages will hereinafter appear.

In the accompanying drawings, Figure 1 is a diagrammatic front elevation of a generator embodying the present improvements in one form.

Figure 2 is a part-sectional front elevation of the apparatus.

Figure 3 is a part-sectional side elevation.

Figure 4 is a diagrammatic plan of the water and steam drums, showing in section the valve mechanism for automatically controlling the direct connection between said drums; the valve being shown closed.

Figure 5 is a detail to show the valve open which is closed at Figure 4.

Figure 6 is a part-sectional plan of the apparatus.

Figure 7 is a diagrammatic sectional detail of a throttle valve for the pump which feeds the generator; illustrating the means for automatically exhausting the steam from the steam chest of the pump when the pump is closed down.

Figure 8 is a diagrammatic side elevation of the pump, with its steam chest, a steam pipe feeding to said chest, a waste or exhaust pipe for said chest, a pipe leading from said chest to hold the valve closed at Figure 4, and a water delivery pipe which extends from said pump to the generator.

Water is supplied by a steam-driven force pump 20, through a main 21, which has branch mains 22, 23, to feed the water drums

24, 25, placed at the top of the generator, which comprises a front wall 26, a rear wall 27, and side walls 28, 29. From the front ends of said water drums extend headers 30, 31, extending towards the side walls of the furnace, each header being used for distributing water to sections 32 forming grids. Each grid section comprises a coil imbedded in refractory heat-conducting material forming a partition 33. Upward passages 34 for the flames are formed by the partitions, said passages opening into common flues 35, leading to a stack 36. Each of these grid sections comprises a series of horizontal pipes 37, placed one above another, the pipes being connected at their ends by U-fittings or unions 38, in a manner to form a single zigzag course; and in the front wall of the boiler may be arranged screw plugs 39, for all the pipes in each grid section. Said front and rear walls 26, 27, may be made of refractory material; the front and rear ends of the zigzag turns being imbedded in said walls. If desired, the pipes may be arranged in pairs, each pair formed with a bend at its rear end, as seen at Figure 3, and the front ends of the tubes may be arranged with U-fittings having the plugs 39 aforesaid. These water coils are separated, with the flame chamber between them; and the water advances from the portion of the furnace which is remote from the grate 52 and relatively cool, to the portion which is near said grate and relatively hot.

At their lower ends, the sections 32 in the grids open individually into collecting headers 40 which lead to the lower ends of main coils 41. These main coils, like the grid coils, stand upright within the generator, and, like the grid coils, are formed of lengths 42 of piping connected by fittings 43 at their rear ends and by U-fittings 44 at their front ends to form zigzag coils; the upper ends of these coils delivering by means of pipes 45 to the front end of a steam-drum 46, placed at the central upper portion of the apparatus. The water receives the main portion of its heat while it is in the coils. As set forth in said application, there may be provided in the steam-drum a pressure-reducer 47, into which both of the pipes may deliver, and whereby the remainder of the water in the fluid is converted into steam. The fluid up to this stage has been subjected for a considerable period to exceedingly high heat and pressure of say 300 pounds or more per square inch and at this point it issues into the drum 46 as steam and is retained at a somewhat lower pressure in said drum, from which extends a service pipe 48.

Said final heating coils 42 are imbedded in partition walls 49 of refractory heat-conducting material, which form sides of a flame chamber 50, extending from the front wall 130

to the rear wall of the furnace; the rear and front walls at the flame chamber being preferably thickened at 51, as illustrated at Figure 3. At the bottom of the fire-box may 5 be arranged a grate 52, to which access may be had through a door 53; the lower door 54 at Figure 2 opening into an ash pit 55.

- The flames which rise from the fuel in the fire-box pass up to the top of the fire 10 chamber, and then divide and pass down through outer passages 56 alongside of said fire-box walls 49, so that an increased heat is imparted to the fluid as it is forced up through the main coils 41 to the steam-drum. 15 Said passages 56 lead the flames down at each side to lower horizontal flues 57, at the sides of the generator, and from these flues the flames subdivide and rise through outlets 58 to the relatively small passages 34 20 between the partitions 33 in which are imbedded the grid sections or coils. These passages 34 lead at each side to the passage or flue 35 communicating with the stack 36. The inner walls of the flues and the lower 25 portions of the stack may form an arch, so that flames cannot pass up around the drums and escape directly into the stack, but must be diverted into the outer passages and eventually rise through the narrow passages 30 and the flues to the stack.

- When it is desired to use the fire-box apparatus as a gas producer, air may be supplied through conduits 59 extending from front to rear at the lower portion of the 35 side walls 49 of the fire-box, and having openings 60 into the latter. The air may be forced by a blower 61 through a pipe 62. The carbon monoxide from the fire-box passes over the tops of the side walls 49 and 40 down through the passages 56 into the main passages 57 of the lower part of the apparatus; a secondary air-supply conduit 63 being provided for each of said main passages 57, being connected by passages 63 to supply 45 the air necessary for the combustion of the carbon monoxide. The flames from this combustion pass through the narrow upward passages 34, thereby heating the fluid, and finally escape through the flues to the stack. 50 The air-supply pipe 62 may have an elbow 64 to supply air below the grate. Said pipe 62 may cross over the fire door, and open into U-pipes 65 which supply the passages 59 and 63. Fuel may be introduced through 55 the upper door 65^a seen at the front of the furnace.

- For the purpose of temporarily providing a circulation in the steaming system in case it should become necessary to close down the 60 force pump 20, there is provided a by-pass or direct connection between the three drums, which connection is closed during the ordinary steaming operation. This connection comprises a cross main 66 extending 65 from one water-drum 24 to the other 25,

having at its ends elbows to connect with the ends of said drums, and having at its middle portion a short pipe or fitting 67 to connect it to the end of the steam-drum 46, which is located between the water-drums. This 70 connection enters the end of the steam-drum at its lower part, and enters the ends of the water-drums at their upper portions, thereby conducing to effective circulation when required. Normally this cross main 66 is 75 entirely closed, so that no direct communication occurs between the water-drums or from the steam-drum to the water-drums. This closing may be effected by any suitable means, and, if desired, may be under 80 the control of an attendant. However, the opening and closing of this communication between the drums is preferably automatic, and preferably comprises a slide valve 68 which is movable endwise in the cylinder or 85 fitting 67 which connects said cross main to the steam-drum. This valve fits closely in said cylinder, and therefore closes the passage through the main 66 from water-drum to water-drum, so that no water can circulate 90 between said water-drums. At the same time the valve closes the passage between the steam-drum and said cross main, which passage consists of said cylinder or cylindrical fitting, thus entirely closing direct 95 communication. Said valve, which is movable endwise in said cylinder, that is, in the direction of the length of the steam-drum, is held closed by means of steam pressure 100 acting upon a piston 69, which is of greater diameter than the valve 68, and fits in an enlarged cylinder 70, and is connected with said valve 68 or forms a continuation thereof. The large cylinder 70 is supplied with steam through a pipe 71 which enters the 105 head of the cylinder and leads from the steam chest 72 of the force pump 20. So long as the pump is in operation, the pressure of steam delivered through said pipe 71 to said cylinder presses against the piston 110 69, and holds the valve in closed position at Figure 4. The steam in the steam-drum tends constantly to force said valve 68 in the opposite direction, but the piston 69 is of greater diameter than the valve, and hence 115 the pressure of steam from the pump chest against the piston overbalances the pressure of steam from the drum in pressing in the opposite direction against the valve, so that the latter is kept closed. When, however, 120 the engineer, by turning a hand-wheel 73, closes a throttle valve 74 in the steam pipe 75 that supplies the pump, the stem 76 of said valve, in moving endwise, is arranged to exhaust the steam from the steam chest 72 125 of the force pump; and hence the pressure in the cylinder 70 is reduced so that the piston 69 can no longer retain the valve 68 closed; but the direct pressure of steam from the steam-drum acts upon said valve, and 130

pushes the same out to the position at Figure 5, and ports 77 in said valve come into communication with the opposite portions of the cross main 66 between the water-drums, thereby establishing direct communication between said drums. Moreover, the valve 68 is hollow, so that a passage is also opened between the steam-drum 46 and both of the water-drums, as will be understood from Figure 5. Thus communication is automatically established between the three drums whenever the pump is shut down, and since the water drums are in open communication with the side tubes and the steam drum with the inner tubes any abnormal pressure at any part of the system can be transmitted through the drums and tubes to relieve the localized pressure and danger of injury to the pipes or drums through the forming of stationary steam bubbles during the closing down of the pump is thus avoided.

The device which automatically exhausts the steam from the steam chest of the force pump comprises the stem 76 of the throttle valve 74, and a cylindrical valve 78 which is carried upon the inner end of said stem, and has a peripheral groove 79 forming a steam passage, which groove is normally closed by the walls of the cylinder 80 in which said valve works. Said cylinder 80 extends from one side of the valve casing 81 in the steam supply pipe 75. When said throttle valve 74 is closed, the valve 78 is displaced far enough to bring the groove 79 therein into communication with ports 82 provided in the sides of said cylinder 80, thereby opening an exhaust or waste pipe 81^a which leads from said steam chest 72, as at Figure 7, so that steam is exhausted from said chest, and hence pressure is reduced in the pipe 71 and in the cylinder 70 in which works the piston 69, so that, owing to the unbalanced condition of the valve 68, the steam from the steam-drum is enabled to force the same to open. Upon opening the throttle valve 74 and starting the pump 20, the valve 78 is moved so far to the right, from Figure 7, as to bring the groove 79 therein out of register with the ports 82 in the cylinder, thus closing the exhaust pipe 81^a, so that steam is maintained at working pressure in the chest 72 of the pump, and hence steam pressure rises again in the pipe 71 which leads from the chest to the cylinder 70 at the end of the steam-drum, and the pressure from the oversized piston 69 on said cylinder forces the valve to position shown at Figure 4, thereby again closing direct communication among the three drums.

Variations may be resorted to within the scope of the invention, and portions of the improvements may be used without others.

Having thus described my invention, I claim:

1. A steam-generator having an interior flame-chamber, the latter comprising front, rear and side walls, a system of piping including coils in said side walls and also including other coils exterior to said walls but within said generator, a steam-drum to which said side-wall coils deliver, and a pump by which the fluid is forced only once in a single direction through said coils to said steam-drum; provision being made at the terminal end of the piping system for converting any remaining water of the high heated high pressure pent up advancing fluid into steam.

2. A steam-generator having an interior flame-chamber, the latter comprising front, rear and side walls, a system of piping including coils in said side walls and also including additional coils, a steam-drum to which said side-wall coils deliver, and a pump to force fluid through said additional coils and then through said side-wall coils to said steam-drum, means for reserving fluid being included between said pump and said additional coils.

3. A steam-generator having an interior flame-chamber, the latter comprising front, rear and side walls, each side wall containing a coil of piping, said coils together with additional coils forming a fluid-pipe system, a pump to force fluid under high pressure only once in a single direction through said system, and a steam-drum at the delivery end of said fluid-pipe system, flame-passages being provided over the top and down along side of said side walls, so that the latter are heated on both sides, and so that the flames and hot gases may have access to said additional coils, provision being made at the terminal end of the piping system for converting any remaining water of the high heated high pressure pent up advancing fluid into steam.

4. A steam-generator having an interior flame-chamber, the latter comprising front, rear and side walls, each side wall containing a coil of piping, said coils together with additional coils forming a pipe system, a pump to force fluid under high pressure only once in a single direction through said system, and a steam-drum at the delivery end of said pipe system, flame-passages being provided over the top and down alongside of said side walls, so that the latter are heated on both sides, and so that the flames and hot gases may have access to said additional coils; and provision being made at the terminal end of the piping system for converting any remaining water of the highly heated high-pressure pent-up advancing fluid into steam. the coils in said walls constituting the terminal portion of the piping system.

5. A steam-generator comprising a flame chamber having front, rear and side walls, coils imbedded in said side walls, partitions to form passages for the flames outside of said side walls, coils of piping imbedded in

said partitions and connected at their delivery ends to the coils in said side walls, water-reserve drums delivering to said partition coils, a steam-drum collecting from 5 said side wall coils, and a force pump to advance fluid through said water-drums and said coils to said steam-drum.

6. A steam-generator comprising a flame chamber having front, rear and side walls, 10 coils imbedded in said side walls, partitions to form passages for the flames outside of said side walls, coils of piping imbedded in said partitions and connected at their delivery ends to the coils in said side walls, water- 15 reserve drums delivering to said partition coils, a steam-drum collecting from said side wall coils, and a force pump to advance fluid through said water-drums and said coils to said steam-drum, passages being pro- 20 vided over the tops of said side walls and beneath said partitions, and escape flues leading from said partitions.

7. A steam-generator comprising a flame chamber having front, rear and side walls, 25 coils imbedded in said side walls, partitions to form passages for the flames outside of said side walls, coils of piping imbedded in said partitions and connected at their delivery ends to the coils in said side walls, water- 30 reserve drums delivering to said partition coils, a steam-drum collecting from said side wall coils, and a force pump to advance fluid through said water-drums and said coils to said steam-drum, said steam-drum being 35 placed above said flame chamber or fire-box, and said water-drums being placed at the sides of said steam-drum above said partitions.

8. A steam-generator comprising a flame 40 chamber having front, rear and side walls, coils imbedded in said side walls, partitions to form passages for the flames outside of said side walls, coils of piping imbedded in said partitions and connected at their delivery 45 ends to the coils in said side walls, water-reserve drums delivering to said partition coils, a steam-drum collecting from said side wall coils, a force pump to advance fluid through said water-drums and said 50 coils to said steam-drum, distributing headers extending from said water-drums to the coils in said partitions, and collecting headers leading from said partition coils to the coils in said side walls.

55. 9. A steam-generator comprising a flame chamber having front, rear and side walls, coils imbedded in said side walls, partitions to form passages for the flames outside of said side walls, coils of piping imbedded in 60 said partitions and connected at their delivery ends to the coils in said side walls, water-reserve drums delivering to said partition coils, a steam-drum collecting from said side wall coils, and a force pump to ad- 65 vance fluid through said water-drums and

said coils to said steam drum, the piping in all of said coils extending into the front wall of the furnace, and plugs being provided at the front wall for all of said piping.

10. A steam-generator having front, rear 70 and side walls and containing a central flame chamber having side walls, fluid coil embedded therein with passages for the flames over the tops of the last-mentioned side walls, partitions between the side walls 75 of the flame chamber and the side walls of the furnace, passages being provided below said partitions, coils of fluid-piping imbedded in said partitions, a steam-drum to which the fluid advances through the coils 80 in said partitions, a water-reserve means connected to the intake ends of said coils, and a pump to force fluid to advance through said coils to said drum.

11. A steam-generator having front, rear 85 and side walls and containing a central flame chamber having side walls, with passages for the flames over the tops of the last-mentioned side walls, coils imbedded in said side walls, partitions between the side walls of the flame chamber and the side walls of the furnace, passages being provided below 90 said partitions, coils of fluid piping imbedded in said partitions, a steam-drum to which the fluid advances through the coils 95 in said partitions and in the side walls of said flame chamber, a water-reserve means connected to the intake ends of said partition coils, a pump to force fluid to advance 100 through all said coils to said drum, distributing headers between said water-reserve means and said partition coils, and collecting headers connected to said partition coils 100 and to said steam-drum.

12. A steam-generator having front, rear 105 and side walls with coils therein and containing a central flame chamber having side walls, with passages for the flames over the tops of the last-mentioned side walls, partitions between the side walls of the flame 110 chamber and the side walls of the furnace, passages being provided below said partitions, coils of fluid piping imbedded in said partitions, a steam-drum to which the fluid advances through the coils in said partitions, a water reserve means connected to the intake ends of said coils, and a pump to force fluid to advance through said coils to said drum, said water reserve means comprising a pair of drums at the sides of said 115 steam-drum, the latter being arranged over the flame chamber.

13. A steam-generator having front, rear and side walls and containing a central flame chamber having side walls, with passages 120 for the flames over the tops of the last-mentioned side walls, partitions between the side walls of the flame chamber and the side walls of the furnace, passages being provided below said partitions, coils of piping 125

- imbedded in said partitions, a water reserve means connected to the intake ends of said coils, distributing headers between said water reserve means and said coils, collecting headers connected to said coils, coils imbedded in the side walls of said flame chamber and connected to said collecting headers, a steam-drum to which the last-mentioned coils are also connected.
- 10 14. A steam-generator comprising a steam-drum, a force pump, a system of piping through which water is forced only once in a single direction by said pump, a water-reserve drum being included in said system, a flame-chamber arranged within said generator and having a side wall, a coil included in said system and imbedded in the side wall of said flame-chamber and connected to deliver to said steam-drum, a second coil also included in said system and exterior to said side wall and within the generator and connected to receive fluid from said water-reserve drum and deliver it to the first coil, a flame-passage being arranged at the top of said wall, to permit the flames to flow over and descend by the side of said wall, and a partition in which the second
- 5 coil is imbedded, a passage being left at the bottom of said partition, so that the descending flames and gases may rise on the other side of said partition; and provision being made at the terminal end of the piping system for converting any remaining water of the highly heated high-pressure pent-up advancing fluid into steam. 30
- 15 15. A steam generator having an internal flame chamber, a force pump, a system of piping thru which fluid is forced only once in a single direction by said pump, said system including coils between which said flame chamber is arranged and means between the force pump and said coils for containing a reserve body of water, partitions in which said coils are embedded, said flame chamber having side walls, other coils 40 also included in said system and embedded in said side walls to receive fluid from the first mentioned coils, and a steam drum, provision being made at the terminal end of the piping system for converting any remaining water of the highly heated high-pressure 45 pent-up advancing fluid into steam. 50

HENRY A. NICHOLSON.
